TRANSFER MECHANISM FOR BOOK MATCH MACHINES

Original Filed April 6, 1927 3 Sheets-Sheet 3

UNITED STATES PATENT OFFICE

LUCIAN E. PARKER, OF WADSWORTH, OHIO, ASSIGNOR TO THE OHIO MATCH COMPANY, OF WADSWORTH, OHIO, A CORPORATION OF OHIO

TRANSFER MECHANISM FOR BOOK-MATCH MACHINES

Original application filed April 6, 1927, Serial No. 181,478. Divided and this application filed June 6, 1929. Serial No. 368,969.

This case is a division of my application for patent for machines for assembling book matches, filed April 6, 1927, Serial No. 181,478, patented March 11, 1930, No. 1,750,281.

The invention relates to a transfer and counting mechanism for book match machines; that is to say, mechanism whereby the finished match books may be arranged in proper order and counted off in proper predetermined multiples for packing.

Machines for manufacturing book matches or, more particularly, machines for assembling the cards of matches and their covers to form match books, are generally so designed as to discharge the finished books in uniform order. This results in the necessity for providing some means whereby alternate books in a uniform series of same may be turned end-for-end so that, consequent to their characteristic wedge shape, they may stack evenly and be in proper arrangement for packing.

Moreover, book matches are customarily packed in boxes of fifty books, arranged in two rows of twenty-five books each, and if means are provided for automatically counting off the finished and properly arranged match books in multiples of twenty-five books they may be easily and expeditiously handled and packed in such boxes.

The present invention contemplates, therefore, mechanism, adapted preferably for association or combination with book match machines, adapted to so operate upon a progressive uniform series of finished match books as to turn alternate books of such series end-for-end so that they may stack evenly, and means for counting off the match books in the customary multiples of twenty-five, or other desired multiples, as I will proceed now to explain and finally claim.

In the accompanying drawings illustrating the invention, in the several figures of which like parts are similarly designated, Figure 1 is a fragmentary plan view of a portion of a book match machine embodying the mechanism of my invention. Fig. 2 is a sectional elevation taken on line 2-2 of Fig. 1. Fig. 3 is a sectional elevation taken on line

3-3 of Fig. 1. Fig. 4 is an enlarged fragmentary sectional elevation illustrating the manner of and means for so spacing the match books that they are counted off in multiples of twenty-five (or other desirable multiples).

The finished books of matches *a* are discharged from the book match machine into a travelling conveyor *b*. This conveyor comprises an endless chain of links 1 pivoted together in the usual manner at 2 and travelling over complementary sprockets, only one of which sprocket 3 is shown. The sprocket 3 is driven with a step-by-step or intermittent motion by means of suitable gearing in timed relation to the book match machine.

Each link 1 of the conveyor chain is provided with two fins or fingers 4, each pair of same forming a compartment in the conveyor for the reception of a match book from the discharge mechanism of the book match machine during the travel of the conveyor.

All of the match books discharged by the discharge mechanism fall into the compartments of the conveyor with their broad ends facing in the same relative direction, and as, in packing, it is desirable to have every alternate book reversed end-for-end so that the books will stack evenly, I provide the mechanism next described.

As the conveyor *b* travels in the direction of the arrow (Fig. 1) it passes beneath a sweep 5 carried by a shaft 6. This shaft is rotated by means of bevel gearing 7 driven by chain and sprocket gearing 8 from a shaft 9 connected with and driven in timed relation to the book match machine and hence to the conveyor *b*. Each end of the sweep 5 carries a brush 10, and these brushes will alternately, during the rotation of the sweep, remove match books from alternate compartments of the conveyor *b* and push them around in an arcuate channel guide 11 until they again enter the conveyor in compartments thereof which it has previously made vacant. The exit end 12 of the channel guide is provided with a resilient member 13 forming one of its wall, whereby jamming of the match books is prevented. In order to prevent the brushes 10 from disarranging the

100

match books after the latter have been reintroduced into the conveyor by them, I provide a guard 14 overlying the conveyor and match books and over which the brushes ride out of contact with the match books.

As the conveyor 3 travels around with the sprocket 3, the match books are deposited upon a chute 15 provided therefor and having a slot 16 embracing the sides of the conveyor chain and hence of less width than the length of the match books, whereby the ends of the match books overlying the sides of the chain will be engaged by the bottom of the chute adjacent to the slot 16 and lifted out of the compartments of the conveyor.

The counting of the match books in predetermined multiples, multiples of twenty-five for example, is readily accomplished by 20 making the follower fin or finger 17 (Figs. 3 and 4) of every twenty-fifth compartment a little longer than the other fins or fingers 4, whereby every twenty-fifth book of matches is pushed a little further along the chute 15 than the other books. This indicates distinctly, as indicated at *c* (Fig. 4) the point of separation between multiples of twenty-five books, and leaves a slight space which enables an operative to readily grasp twenty-five books of matches between the fingers, without having to count them. This, as will be apparent, greatly facilitates and expedites the packing operation.

Various changes in details of construction 35 and arrangement of parts are deemed to be within the spirit of the invention and the scope of the following claims.

What I claim is:—

1. In a transfer mechanism for book match 40 machines, a traveling conveyor provided with means defining a plurality of compartments each of which is adapted to receive a match book, and means for removing such match books from alternate compartments and replacing them in other compartments in endwise reversed position.

2. In a transfer mechanism for book match 50 machines, a travelling conveyor provided with means defining a plurality of compartments each of which is adapted to receive a match book, and means for removing match books from alternate compartments at one point in the travel of the conveyor and replacing them at another point and in endwise reversed position in compartments previously made vacant.

3. In a transfer mechanism for book match 60 machines, a travelling conveyor provided with compartments each of which is adapted to receive a match book, and means for removing alternate books from said conveyor, turning them end-for-end and reintroducing them into said conveyor including a guide having its ends adjacent to said conveyor and a sweep rotatable in timed relation to the

travel of the conveyor, said sweep operating to remove match books from said carrier at one end of said guide, propel them through said guide and insert them in said conveyor at the other end of said guide, the books in their travel through said guide being turned end-for-end relatively to said conveyor. 70

4. In a transfer mechanism for book match machines, an intermittently travelling conveyor provided with compartments each of which is adapted to receive a match book, and means for removing alternate books from said conveyor, turning them end-for-end and reintroducing them into said conveyor including an arcuate guide having its ends adjacent to said conveyor and a sweep rotatable in timed relation to the travel of the conveyor, said sweep operating to remove match books from said conveyor at one end of said guide, propel them through said guide and insert them in said conveyor at the other end of said guide, the books in their travel through said guide being turned end-for-end relatively to said conveyor. 75 80 85

5. In a transfer mechanism for book match machines, a traveling conveyor provided with means defining a plurality of compartments therein each compartment adapted to receive a match book, and a chute for receiving the books from said conveyor, one of the compartment-defining means at each of a plurality of predetermined points on said conveyor being longer than the others of said means intervening, whereby the books received upon the chute will be arranged in predetermined multiples indicated by the separation thereof caused by the action of said longer compartment-defining means. 90 95 100 105

In testimony whereof I have hereunto set my hand this 4th day of June, A. D. 1929.

LUCIAN E. PARKER.
